UNITED STATES PATENT OFFICE.

CHARLES T. BROWN AND FRED W. LEUTHESSE, OF CHICAGO, ILLINOIS,
ASSIGNORS TO MONASH-YOUNKER COMPANY, OF SAME PLACE.

DESIGN FOR A STEAM-TRAP.

SPECIFICATION forming part of Design No. 34,878, dated July 30, 1901.

Application filed May 10, 1901. Serial No. 59,707. Term of patent 14 years.

To all whom it may concern:

Be it known that we, CHARLES T. BROWN and FRED W. LEUTHESSE, citizens of the United States, residing at Chicago, in the county of Cook and State of Illinois, have invented and produced a new and original Design for a Steam-Trap, of which the following is a specification, reference being had to the accompanying drawings, forming a part hereof.

10 Figure 1 is a perspective view of a steam-trap, showing our new design; and Fig. 2 is an end elevation thereof.

The leading features of our design consist of a cylindrical body A A', having circular or rounded ends B B', the axis of such cylindrical body A A' and the axes of the ends B B' being at substantially right angles, (whereby the contourlines *ab ab* are obtained,) with horizontal flanges C C' extending longitudinally entirely around the steam-trap a short distance above the center of the cylindrical body, with lugs or projections on the lower half of the cylindrical body A A' con-

stituting the legs K K of the steam-trap, and with projecting lugs or bodies E G at the ends of the lower half of the cylindrical body A A'. The last-named lugs or projections E and G give the appearance of solidity and massiveness to the parts of the steam-trap where pipe connections for inlet and outlet are ordinarily made and are provided with screw-threaded holes, respectively, for the attachment of such pipes.

Having thus described our invention, what we claim as new, and desire to secure by Letters Patent, is—

The design for a steam-trap as shown and described.

In testimony whereof we have signed our names to this specification in the presence of two witnesses subscribing hereto.

CHARLES T. BROWN.

FRED W. LEUTHESSE.
